UNITED STATES PATENT OFFICE.

EDWARD CLIFF, OF NEWARK, NEW JERSEY, ASSIGNOR TO THE CLIFF & GUIBERT COMPANY, OF NEW YORK, N. Y.

DESIGN FOR A WALL-BRACKET.

SPECIFICATION forming part of Design No. 32,336, dated March 13, 1900.

Application filed February 12, 1900. Serial No. 5,015. Term of patent 14 years.

To all whom it may concern:

Be it known that I, EDWARD CLIFF, a citizen of the United States, residing at Newark, in the county of Essex and State of New Jersey, have invented and produced a new and original Design for a Wall-Bracket, of which the following is a specification, reference being had to the accompanying drawings, forming a part thereof, and in which—

10 Figure 1 is a side elevation of a wall-bracket bearing and incorporating my design, and Fig. 2 is a vertical section of same on the dotted line 2 2 of Fig. 1.

15 The leading feature of my design consists in the form and configuration of the wall-bracket, substantially as shown in the drawings.

20 In the drawings, A designates the bracket as a whole, said bracket comprising the vertically-elongated wall-plate B and the upper and lower horizontal arm-sections C C, ex-

tending outward from said plate B. The arm-sections C C correspond in outline with one another. Their sides taper toward one another from the plate B outward, and the upper edge of the upper arm and the lower edge of the lower arm also taper or incline toward one another from the plate B outward. The upper surface of the upper arm C and the lower surface of the lower arm C present 25 rounded surfaces, as shown in Fig. 2, and the surfaces of said arms C C present the appearance of being in strong relief.

What I claim is—

25 The design for a wall-bracket, substantially as shown and described.

Signed at New York, in the county and State of New York, this 10th day of February, 1900.

EDWARD CLIFF.
